UNITED STATES PATENT OFFICE.

JACOB NORTH, OF CLINTON, ILLINOIS.

CLEANING IMPLEMENT.

1,117,513.

Specification of Letters Patent. Patented Nov. 17, 1914.

Application filed February 19, 1914. Serial No. 819,820.

To all whom it may concern:

Be it known that I, JACOB NORTH, a citizen of the United States, residing at Clinton, in the county of DeWitt and State of Illinois, have invented a new and useful Cleaning Implement, of which the following is a specification.

The present invention relates to improvements in cleaning implements, one object of 10 the invention being the provision of an implement especially designed to be used in connection with a cleaning and polishing windows, the said implement being provided with means 15 for directing the fluid upon the window and for directing water also upon the window, in combination with a pivoted head carrying a clamping means for the reception of a scraper and a squeegee, whereby the window 20 may be operated upon to have its surface cleaned and polished.

A further object of the present invention is the provision of an implement of this character, in which the clamping head is 25 pivotally mounted in a peculiar shaped frame, which constitutes a sliding guide for the nozzle for introducing the fluid, said nozzle being disposed for movement beyond and within the cleaning range of the clamping head.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without 40 departing from the spirit of the invention.

In the drawings—Figure 1 is a perspective view of the complete implement, the manipulating handle being foreshortened. Fig. 2 is a side elevation of the same on a 45 reduced scale showing a mop cloth secured in the clamping head. Fig. 3 is a side elevation of the present implement, when used in connection with the fluid introducing or spraying means. Fig. 4 is a central cross section through the clamping head and the supporting frame. Fig. 5 is a cross section 50 taken on line 5—5 of Fig. 3.

Referring to the drawings, the numeral 1 designates the disk which is provided with 55 the sleeve 2 and a set screw 3 for the slide- able and adjustable reception of the pipe 4,

which constitutes a fluid directing pipe and also the handle for the present device.

Adjustably attached upon the handle 4 is a sleeve 5 having the rubber gasket 6 fixed 60 so as to act as a buffer or bumper to reduce the jar, when the disk 1 is slid downwardly to permit the nozzle 9 to be projected as illustrated in Fig. 3. A coupling 7 is connected to the free end of the pipe 4 beyond 65 the disk 1 and has a gasket 8 surrounding the pipe 4 adjacent the connection thereof for abutment with the sleeve 2 to relieve the jar when the nozzle 9 is retracted fully within the frame or slightly greater than 70 illustrated in Figs. 1 and 2.

A clamp for carrying the nozzle and also for guiding the same in its movement consists of the two members 10 and 11, the central portion of which is clamped about the 75 coupling 7 by means of the screws or bolts 12, while the two terminals 13 constitute sleeves which are mounted slidably upon the two parallel rods 14, which are secured rigidly by means of the nuts 15 at diametrically 80 opposite points to the disk 1.

The two arms 14 which constitute a frame or support for the clamping head, as will presently appear, are connected together by the cross bar 16 which due to the bends 17 85 is set at an abrupt angle to the rods 14, the purpose of which will presently appear. Mounted upon the cross bar 16 is the sleeve 18 which is carried by the clamping member 19, thus permitting the clamping member 19 to assume the various positions illustrated. A set screw 20 is provided for locking the clamping member 19 in the desired positions. The clamping plate 21, is disposed in co-operative relation to the plate 19, 90 the sleeve 18 acting as a fulcrum point between the two, so that the respective free terminals of cross heads 22 and 23, and 26 and 27 are normally separated, their respective clamping screws 24 and 29 being provided to move the heads 22 and 23, and 26 and 27 together to provide two oppositely disposed clamping heads, one for the reception of the squeegee member 25 and the other for the dusting or brush member 30. 95 100 105

By providing the curved portions 17 in the arms 14, the squeegee member 25 when in the position for operating, is properly locked by the engagement of the arms 14 with the under side of the clamping plate 110 27, as particularly illustrated in Figs. 1, 2 and 4.

An auxiliary clamping plate 31, which is secured to the outer face of the plate 22 by means of the screws 24, is disposed to be readily adjusted for the reception of a mop cloth or rag 32, as illustrated in Fig. 2, so that such cloth may be used to supplement the squeegee, or alone, as may be desired.

When using the present device, for cleaning windows, the implement is operated so that the nozzle 19 is projected as illustrated in Fig. 3, at which time the cleaning and polishing fluid is introduced through the nozzle 9 and sprayed upon the window to be cleaned. After the window has been properly sprayed therewith, water is next sprayed upon the window through the nozzle 9, and then the nozzle is caused to assume the position, as shown in Figs. 1 and 2, so that either one of the cleaning members 25 or 30, preferably the squeegee 25 may be clamped to assume the desired angle for cleaning the window.

What is claimed is:

1. A cleaning implement, including a supporting and guiding member, a clamping head composed of a plurality of securing means pivoted to the same, a tubular handle slidably mounted in the supporting member, and a nozzle carried thereby for introduction beyond and within the plane of action of the clamping head.
2. A cleaning implement, including a disk having a collar, a tubular handle slidably mounted therethrough, a nozzle carried upon one end of the handle, a frame carried by the disk and disposed to fit astride the nozzle, coöperating means carried by the frame and the nozzle for guiding the same therebetween, and a pivoted mop member carried at the free end of the frame.
3. A cleaning implement, including a disk having a collar, a tubular handle slidably mounted therethrough, a nozzle carried

upon one end of the handle, a frame carried by the disk and disposed to fit astride the nozzle, coöperating means carried by the frame and the nozzle for guiding the same therebetween, a pivoted mop member carried at the free end of the frame, said pivoted member including two H-shaped plates, and means for clamping the coactive parallel members thereof to constitute a cleaner holder.

4. A cleaning implement, including a tubular member, a disk slidably mounted thereon, a frame having two terminals, the free ends of which are connected to the disk and the connected end of which is disposed at an obtuse angle to the body thereof, a nozzle connected to the tubular member and disposed between the parallel members of the frame, and a cleaning head pivotally connected to the cross bar of the connected end of the frame.

5. A cleaning implement, including a tubular member, a disk slidably mounted thereon, a frame having two terminals, the free ends of which are connected to the disk and the connected end of which is disposed at an obtuse angle to the body thereof, a nozzle connected to the tubular member and disposed between the parallel members of the frame, a cleaning head pivotally connected to the cross bar of the frame, a pivoted mop member carried at the free end of the frame, said pivoted member including two H-shaped plates, and means for clamping the coactive parallel members thereof to constitute a cleaner holder.

In testimony that I claim the foregoing as my own, I have hereto affixed my signature in the presence of two witnesses.

JACOB NORTH.
